UNITED STATES PATENT OFFICE

OSCAR WERNER, OF CLEVELAND, OHIO

DESIGN FOR A HEADLIGHT

Application filed November 30, 1931. Serial No. 41,909. Term of patent 7 years.

To all whom it may concern:

Be it known that I, OSCAR WERNER, a citizen of the United States, residing in Cleveland, in the county of Cuyahoga, and State of Ohio, have invented a new, original, and ornamental Design for a Headlight, for use on airplanes, automobiles, and the like, of which the following is a specification, reference being had to the accompanying drawing, forming part thereof.

Figures 1, 2, and 3 are a side view, a front

view and a plan view, respectively, of a headlight embodying my design, the major portion of the headlight having the appearance of a smooth, stream lined form divided substantially upon its major axis.

I claim:

The ornamental design for a headlight, as shown and described.

Signed by me this 28th day of November, 1931.

OSCAR WERNER
